FORREST A. WALKER, OF SYRACUSE, NEW YORK, ASSIGNOR TO WALKER DISHWASHER CORPORATION, OF SYRACUSE, NEW YORK, A CORPORATION OF NEW YORK

MECHANICAL DISHWASHER

Original application filed July 24, 1926, Serial No. 124,640. Divided and this application filed July 2, 1928. Serial No. 289,999.

This invention relates to a mechanical dishwashing machine but more particularly to the construction of the upper dish-supporting tray or basket and its relation to

5 the lower basket and impeller for circulating the washing fluid from the bottom of the vat upwardly as set forth in my pending application Serial No. 124,640, filed July 24, 1926, of which the present application is

10 a division.

In mechanical dishwashers of this type it is found to be expedient and practicable to use at least two dish-supporting trays or baskets so that the dishes or other culinary articles in the baskets may be washed, cleansed and dried in a single operation, one of the baskets being preferably supported upon the bottom of the vat while the other basket is supported at a higher level upon the

20 upper marginal edge of and within the vat.

When the baskets loaded with dishes and other articles are placed in the relation described within the vat preparatory to cleansing, rinsing and drying it frequently becomes expedient or necessary to place additional dishes or to remove some of the dishes into or from the lower basket and, as heretofore constructed and assembled, it usually has not been possible to place or remove 25 dishes from the lower basket without first removing the upper dish-supporting basket with the dishes or other articles thereon which, of course, results in loss of time and extra labor.

35 An object of the present invention is to construct the bottom of the upper basket with a relatively large central opening of sufficient size to permit ordinary dishes to be passed therethrough by hand to and from the lower basket without disturbing the position of either of the baskets in the vat.

Another object is to provide the bottom 40 of the upper basket with an open work flange projecting inwardly from the outer peripheral wall thereof around the central opening

and preferably inclined upwardly and inwardly toward the center or axis for retaining the dishes thereon and against the outer peripheral wall.

Another object is to provide the top of 50 the vat with an inwardly projecting annular flange and to form the upper end of the basket with an outwardly projecting annular flange adapted to rest upon the flanged top of the vat when in operative position and 55 at the same time permit both baskets to be inserted and withdrawn through the opening in the top of the vat.

Other objects and uses relating to specific parts of the machine will be brought out in 60 the following description.

The drawing represents a vertical sectional view of a mechanical dishwasher embodying the features of my invention.

As illustrated, the frame of the machine 65 comprises a substantially rectangular cap or top section —1— forming the top of a circular vat —2— and provided with inner and outer marginal flanges —3— and —4— united by an intermediate roll at the top. 70

This cap or top portion —1— is provided with a central relatively large circular opening —5— and an inwardly projecting horizontal ledge —6— surrounding the opening for receiving and supporting a lid or cover 75 —7— and an upper tray or basket —8—, said opening being of sufficient size to permit the passage therethrough of the basket —8— and additional tray or basket —9—. 80

The lower face of the ledge —6— is rabbed throughout its length for receiving the upper end of the vat —2— which is clamped to the underside of the cap section —1— by bolts —10—, the latter being arranged in spaced relation circumferentially around the 85 marginal edges of the upper end of the vat.

These bolts are preferably hinged to apertured lugs —11— on the underside of the top section —1— and are movable in slotted lugs —12— on the upper end of the vat to facilitate

tate the assembling of the parts —1— and —2—, one upon the other.

The flange —4— at the rear side of the top section —1— is provided with vertical slots —13— opening from the bottom upwardly for receiving L-shaped bolts or screws —14— which are adapted to be screwed into the side walls as —A— of a room or to any other suitable upright standard, the inner ends of the screws or bolts —14— being preferably turned upwardly to enable the rear flange to be engaged therewith by a downward movement or removed therefrom by upward displacement.

The cap or top section —1— is, therefore, supported at its rear side directly upon the wall —A— while the vat —2— is supported at its upper end entirely by the top —1— through the medium of the bolts —10— and when placed in operative position projects some distance above the lower edge of the marginal flange —4— so that the joint between the two sections will be concealed by said flange.

The lid or cover —7— is made in the form of a shallow inverted cup which is circular in plan and of slightly less diameter than the interior diameter of the annular flange —3— so as to rest upon the upper face of the ledge —6—.

The vertical depth of the cover is slightly less than the corresponding depth of the flange —3— above the ledge —6— and is provided with a substantially flat, upper face which, when the lid is closed lies in a horizontal plane slightly below the upper edge of the cap section —1— to be used when closed for supporting various articles and also to prevent the upward displacement of the washing fluid when circulated in the vat by the impeller mechanism, presently described.

The rear side of the cover —7— is provided with hinge sections —15— which are pivoted at —16— to suitable lugs on the adjacent portions of the top section —1— to permit the lid to be swung from a closed horizontal position upwardly and rearwardly beyond a vertical position or against the inner face of the wall —A—.

The main body of the vat —2— is slightly tapered downwardly and is provided with an inverted conical bottom —17— having an opening in its apex for receiving a bushing —18—, a post —19— and an impeller shaft —20—, the upper end of the bushing —18— being enlarged and engaged with the upper face of the adjacent portion of the bottom —17— to form a water-tight joint therewith, said bushing being extended downwardly some distance below the bottom and threaded externally for receiving a nut —21— which, together with the bushing and suitable packing —22—, constitutes a gland for the reception of the post —19—.

This post extends through and some dis-

tance above and below the bushing —18— and preferably above the level in the vat as regulated by an overflow (not shown).

An angular bracket —23— extends across the underside of the bottom of the vat —2— from the axis toward the rear side thereof and has its rear end attached to the underside of the overlying portion of the vat by means of a strap —24— and bolts —25—.

The front end of the bracket —23— extends under the apex of the bottom —17— and is provided with a gear chamber —26— for receiving a gear —27— which is secured to the lower end of the upright impeller shaft —20—.

The lower end of the tubular post —19— extends into an opening —28— in the top wall of the gear chamber —26— while the shaft —17— extends through and some distance below the tubular post —19— and has its lower end seated on an end-thrust bearing —29— in the bottom wall of the gear chamber —26—, said bearing —29— being seated in the lower end of a socket —30— which receives the lower end of the shaft —20— and holds the latter against lateral movement.

The bottom wall of the gear chamber —26— is made separate from the top wall to permit access to the gear and is secured thereto by screws or bolts —31—, to firmly hold those parts in fixed relation to each other when adjusted for use.

The front end of the bracket —23— is supported by a sectional leg —32— consisting of an upper tubular section —33— and a lower section —34—, the section —33— being threaded internally while the section —34— is threaded externally for engaging the internal threads and permitting the length of the leg to be adjusted as may be required for properly supporting the inner end of the bracket —23—.

The leg —32— is coaxial with the axis of the vent —2—, the post —19— and shaft —20— and serves not only to partially support the vat through the medium of the bracket —23— and connection —24— and also through the medium of the post —19— but also serves to resist the downward thrust of the impeller shaft —20— through the end-thrust bearing —29— due to the lifting action of the impeller upon the water.

The shaft —20— extends upwardly above the upper end of the tubular post —19— and is threaded at its upper end for receiving and supporting an impeller —35—.

This impeller is provided with a central hub open at the bottom and closed at the top which latter is provided with a threaded socket engaged by the upper threaded end of the shaft —20— for transmitting rotary motion from the shaft to the impeller.

The impeller is provided with opposite wings or vanes —36—, the lower edges of

which travel in close proximity to the upper surface of the conical bottom —17—, said blades being provided with baffles —37— projecting in the direction of rotation to limit the centrifugal throw of the water as the impeller is revolved and also to assist in deflecting the water upwardly through the trays —9— and —8— and against any dishes or utensils which may be supported in the trays, the tray —9— being supported upon the outer marginal edge of the inclined bottom —17—.

Power means

15 An electric motor —61— is secured by bolts —62— to the underside of the rear portion of the bracket —23— and preferably directly below the connecting strap —24—, said motor having its armature shaft —63— provided with a worm meshing with the gear —27— for transmitting rotary motion to the impeller shaft —20—.

The bottom section of the gear chamber —26— is somewhat tapered while the upper section —33— of the leg —32— is hollow and adapted to receive the apex of the bottom section of the gear chamber and to abut against the same whereby, when the lower section —34— is adjusted to contact with the floor, the upper section may be adjusted to firmly engage and support the lower section of the gear chamber and thereby to partially support the bracket —23— and vat —2— in addition to its other function of resisting the downward thrust of the impeller shaft —20— particularly when the impeller is in action for lifting and circulating the water circumferentially by centrifugal force within the vat —2— and against any dishes or utensils which may be supported in one or both of the trays —9— and —8— or in a supplemental tray —9'— which is carried by the tray —9—.

It will be noted from the foregoing description that the positioning of the leg —32— directly under the apex of the bottom of the vat —2— and coaxial with the impeller shaft —20— leaves a clear foot space around the front and sides of the leg below the vat so as to avoid contact of the feet therewith in moving around the machine in addition to its other functions of partially supporting the vat and motive power unit and resisting the downward thrust of said shaft due to the lifting action of the impeller upon the water in impelling the same upwardly and centrifugally with a whirling motion.

It will also be observed that when the lid or cover —7— is closed its upper flat surface together with the upper surface of the surrounding portion of the cap section —1— which is in nearly the same horizontal plane affords a convenient work-table for various uses while the general construction of the

machine is simple, free from exposed moving parts and may be easily kept in a thoroughly sanitary condition.

The upper open work wire basket —8— is circular in top plan and open at the top and comprises a series of upright posts —a— arranged in uniformly spaced relation circumferentially about the axis of the basket and having their lower ends electrically welded or otherwise secured to the periphery of a lower ring —b—.

The upper ends of the posts —a— are deflected outwardly at —a'— for engagement with the upper surface of the ledge —6— of the top section —1— for supporting the basket in a plane mainly below said ledge and within the vat and also permitting the basket to be removed by upward displacement through the opening in the ring —1— when the cover —7— is removed.

The posts —a— are connected near their upper ends by a circular ring —c— to assist in holding them in fixed relation, said upper ring being disposed in a plane parallel with the lower ring —b—.

The basket is also formed with an inwardly and upwardly projecting bottom flange —d— composed of a series of rings —d'— and tie rods —d''— extending across the underside of the rings —d— and electrically welded or otherwise secured thereto to hold the rings in radially spaced relation.

The upper inner ring —d'— is of relatively large diameter as compared with the radial width of the bottom flange —d— to form a correspondingly large central circular opening —e— coaxial with the lower basket —9— and of greater diameter than the radius of the opening in the frame section —1— to allow dishes to be passed therethrough into and from the lower basket without disturbing either of the baskets from their normal operative positions within the vat.

It will be noted that the bottom flange —d— is inclined upwardly and inwardly from the lower outer ring —b—, and therefore at an acute angle to the marginal walls of the tray, the purpose of which is to retain the dishes in the basket around the central opening —e—.

The opening in the top section —1— is of sufficiently large diameter to permit both of the baskets —8— and —9— therethrough with the dishes therein.

The construction of the upper basket —8— with the relatively large central opening —e— therein is of particular advantage in this type of machine in which the impeller is used to insert the washing fluid from the bottom upwardly through both of the baskets and against the dishes retained therein for the reason that it is frequently necessary to place additional dishes within the lower basket or to remove some of them from the basket in case they are too congested for effi-

cient cleansing by the circulation of the washing fluid.

What I claim is:

In a mechanical dishwasher, a horizontal frame-section having a circular opening therethrough, a circular vat having its upper end engaging the frame-section around the opening, means for supporting the frame-section independently of the vat, separate means for securing the vat to the frame-section, and a circular openwork dish-supporting tray supported on said frame section within the opening independently of the vat.

In witness whereof I have hereunto set my
15 hand this 26th day of May, 1928.

FORREST A. WALKER.
